DIESEL ENGINE

Konrad Haage, Esslingen-on-the-Neckar, Germany, assignor to "Delmag" Deutsche Elektromaschinen & Motoren-Bau-Aktiengesellschaft, Esslingen-on-the-Neckar, Germany

Application December 7, 1935, Serial No. 53,337
In Germany December 11, 1934

5 Claims. (Cl. 123—50)

My invention relates to internal combustion engines and more especially to two stroke cycle engines operating on the Diesel principle, in which combustion of the mixture of fuel and air is brought about by the heat of compression.

My invention has particular reference to two stroke cycle Diesel engines operated with a comparatively long working stroke and it is one of the objects of this invention to provide means whereby the scavenging and the charging of the cylinder with fresh air can be obtained in a particularly simple and efficient manner.

In the Diesel engines hitherto designed the supply of fresh air for scavenging the cylinder after each combustion and for supplying the necessary air for combustion of the fuel has always been effected by means of positively controlled inflow or outflow ports which have either been valves or slots controlled by the piston or otherwise, such 20 valves or slots having been provided in these engines besides the exhaust slots.

According to the present invention I altogether avoid the provision of separately controlled inflow ports by simply utilizing for the supply of 25 fresh air the exhaust ports which are alternately uncovered and closed in a well known manner by the working piston. In this manner the design of an engine of this kind is greatly simplified and the security of working nevertheless increased.

30 In the drawing affixed to this specification and forming part thereof an engine embodying my invention is illustrated diagrammatically by way of example.

In the drawing,

35 Fig. 1 is an axial section of the working cylinder of the engine with the piston, which is partly shown in elevation, in its upper dead centre position;

40 Fig. 2 is a similar view illustrating the position of the cylinder after it has uncovered the inflow ports for the inflow of fresh air.

Fig. 3 is a cross section on the line A—B in Fig. 2;

45 Figs. 4 and 5 are similar cross sections of two further modifications of my invention.

Referring to the drawing and first to Figs. 1 to 3, in which the new engine is shown as applied to a power ram, *a* is the piston, the bottom end of which is supported by the pile *b* to be 50 driven, while the cylinder *c*, which forms the ram proper, is the part which carries out the working stroke to thereafter drop down and hit the pile *b* or the pile extension *e* mounted thereon.

55 *d* is the piston rod which is fixed in the pile extension *e* by the bottom end *f* of the piston

rod being conically enlarged and seated in a conical boring of the pile extension *e*, a threaded ring *g* being screwed into the bottom end of the pile extension *e* to force the end *f* of the piston rod into its conical seat.

5 A cavity *h* in the pile extension *e* serving as a fuel reservoir is connected by means of a conduit *i* with a fuel pump *k*, the piston rod *m* of which extends into the way of the nose *n* provided near the bottom end of the cylinder *c*. Whenever the piston rod *m* is depressed by the nose *n*, fuel is forced by the pump *k* into the pipe *o*, which extends through a lining *p* in the axial boring *q* of the piston rod *d* and through the piston *a*, so that the fuel forced into the pipe *o* will be conveyed to and injected into the combustion chamber *r* and the cylinder *c*.

10 Fig. 1 illustrates the position of the parts at the moment when fuel is injected into the cylinder and ignited by the heat of compression of the 15 body of air enclosed between the piston *a* and the bottom of the cylinder. The pressure of expansion of the combustion gases lifts the cylinder *c* in the direction of the arrow at the top of Fig. 2, the piston *a* remaining stationary and the 20 working stroke being carried out by the cylinder. As soon as the ascent of the cylinder has uncovered the exhaust ports *s*, which have been 25 carried past the piston *a*, the exhaust gases escape through these ports.

30 However since, owing to the mass inertia, the cylinder continues its ascending stroke, the exhaust of the combustion gases is followed by a suction action, whereby air is now sucked in through the ports *s*. As indicated by the arrows 35 in Figs. 2 and 3, since the ports *s* extend in oblique direction towards the cylinder bottom, the bulk of the fresh air will flow upwardly towards the bottom of the cylinder. The combustion gases, which are still left in the cylinder, have collected 40 close to the piston *a* or are exposed to the sucking action exerted by it.

45 In this manner a mixture containing a sufficient percentage of fresh air is obtained in the cylinder above the ports *s*.

When the cylinder *c*, after having executed its full stroke, starts on its return stroke, the exhaust gases above the piston *a* are expelled for the greater part through the ports *s* until these ports are closed by the piston. The mixture of 50 gas and air in the chamber above the ports is now compressed, until the cylinder has reached the position shown in Fig. 1, when the mixture of air and fuel is ignited by the heat of compression.

Instead of four radially arranged ports as shown in Fig. 3 I may also form the cylinder with three ports which may be arranged as shown in Fig. 4 with their middle axes intersecting at a point 5 located eccentrically to the cylinder axis. In this manner I obtain the formation of eddies in the cylinder which is favorable as far as the scavenging of the cylinder and the refilling with a mixture rich in fresh air is concerned.

10 If, as shown in Fig. 5, the ports extend substantially in tangential direction into the cavity of the cylinder and if they are given the form of suitably configurated guide channels, it is possible to obtain a helical upward movement of the 15 air entering the cylinder along the inner wall, while the gases of combustion flow downwardly in the central zone of the cylinder cavity, being thus enabled to follow the piston *a*. This arrangement has been found to be particularly 20 suitable.

Obviously the present invention is not only applicable to Diesel engines in which, as in the power ram shown by way of example, the cylinder executes the working stroke, but also to engines 25 in which the piston reciprocates as usual relative to the cylinder.

I wish it to be understood that I do not desire to be limited to the exact details of construction shown and described for obvious modifications 30 will occur to a person skilled in the art.

I claim:—

1. A two stroke cycle Diesel engine comprising in combination a cylinder and a piston arranged therein for relative reciprocation, one 35 series of ports provided in said cylinder both for the exhaust of the combustion gases and for the inflow of fresh air, said piston being adapted to control said ports and to perform an additional suction stroke at a value corresponding to the 40 amount of fresh air required.

2. A two stroke cycle Diesel engine comprising in combination a cylinder and a piston arranged therein for relative reciprocation, one series of ports provided in said cylinder both for the ex-

haust of the combustion gases and for the inflow of fresh air, said piston being adapted to control said ports and to perform an additional suction stroke at a value corresponding to the amount of fresh air required, said ports extending in a direction inclined towards the cylinder bottom. 5

3. A two stroke cycle Diesel engine comprising in combination a cylinder and a piston arranged therein for relative reciprocation, one series of 10 ports provided in said cylinder both for the exhaust of the combustion gases and for the inflow of fresh air, said piston being adapted to control said ports and to perform an additional suction stroke at a value corresponding to the 15 amount of fresh air required, said ports being radially arranged so as to cause the air currents entering through the same into the cylinder to intersect at pointed angles.

4. A two stroke cycle Diesel engine comprising 20 in combination a cylinder and a piston arranged therein for relative reciprocation, one series of 25 ports provided in said cylinder both for the exhaust of the combustion gases and for the inflow of fresh air, said piston being adapted to control 30 said ports and to perform an additional suction stroke at a value corresponding to the amount of fresh air required, said ports being arranged so as to cause the air currents entering the cylinder to meet at points within said cylinder which are 35 located eccentrically to the cylinder axis.

5. A two stroke cycle Diesel engine comprising in combination a cylinder and a piston arranged therein for relative reciprocation, one series of 35 ports provided in said cylinder both for the exhaust of the combustion gases and for the inflow of fresh air, said piston being adapted to control 40 said ports and to perform an additional suction stroke at a value corresponding to the amount of fresh air required, said ports extending substantially in tangential direction to the inner surface of said cylinder.

KONRAD HAAGE.
